UNITED STATES PATENT OFFICE.

JOHN H. FEDDEN, OF NEW YORK, N. Y., ASSIGNOR OF ONE-HALF TO
THOMAS A. O'CALLAGHAN, OF HOBOKEN, NEW JERSEY.

STOCKING.

No. 812,168.

Specification of Letters Patent.

Patented Feb. 6, 1906.

Application filed October 9, 1903. Serial No. 176,348.

To all whom it may concern:

Be it known that I, JOHN H. FEDDEN, a citizen of the United States, residing at the city of New York, borough of Manhattan, in the county and State of New York, have invented certain new and useful Improvements in Stockings, of which the following is a full, clear, and exact specification.

My invention relates to improvements in hosiery; and the same has for its object more particularly to provide a stocking so constructed that the same may be used and worn in combination with any supporting device which is worn suspended from or near the waist of the wearer and adapted for engagement with the holding member of said supporting device without danger of injuring the fabric of the stocking.

In practice it has been found that the use of suspended stocking-supporters provided with attaching members adapted for frictional or other engagement with the fabric of the stocking engage such a very limited area of the fabric that the tension thereon due to the elastic of the supporter and the strain due to the moving of the limbs and body of the wearer have the effect to draw unduly upon a few of the longitudinal threads directly in line of the strain and cause the same to be drawn throughout the full length of the stocking and then break and produce openings which render a stocking otherwise serviceable wholly unfit for wear. This has been found to occur almost immediately in the case of delicate or open-work fabrics and within a very short time in the case of heavier fabrics.

Now by means of my invention, which consists in the novel details of construction and in the combination, connection, and arrangement of parts hereinafter more fully described and then pointed out in the claims, I am enabled to attain the objects specified and overcome the disadvantages hereinabove pointed out.

In the accompanying drawings, forming part of this specification, wherein like letters of reference indicate like parts, Figure 1 is a view illustrating a stocking made according to and embodying my invention, showing the manner of supporting the same upon the limb of the wearer. Fig. 2 is a front view of the upper portion of a stocking, showing the relative positions of the attaching portions

thereon. Fig. 3 is a section, greatly enlarged, taken on the line 3 3 of Fig. 2. Fig. 4 is a side view of the upper portion of a stocking, showing a modified shape of attaching portion; and Fig. 5 is a sectional view similar to Fig. 3, showing the attaching portion secured thereto by sewing.

In said drawings, A designates a stocking of usual general construction provided at or near its upper edge upon its outer side near its front with attaching portions B B. These portions B B, I have shown as of a triangular form, with their downwardly-inclined edges a a firmly secured to or incorporated into the fabric of the stocking A and their upper edges arranged parallel to the upper edge of the stocking, but entirely free therefrom, as shown at Fig. 3, so that said portions B B may be grasped between the fingers to produce a fold b, adapted to be engaged by the attaching member C of the supporter D. By means of this attaching portion B, which is preferably made heavier than the body of the stocking, the tension of the elastic supporter D and the strain due to the movement of the limbs or body of the wearer is distributed over a considerable area and instead of drawing only longitudinally of the stocking has a further tendency to draw the upper edge of the stocking laterally together—that is to say, the portion of the fabric of the stocking adjoining the upper ends of the inclined edges a a of the portions B will be caused to approach each other, and thus hold the upper edge of the stocking snugly against the limb.

In the modification illustrated at Fig. 4 I have shown the portion B' similarly secured to the stocking A', but with its apex cut away, and at Fig. 5 I have shown the portion B' secured to the stocking A' along the inclined edges a' a' of said portion by means of rows of stitching c c.

It will of course be understood that the portions B B may be secured by weaving, sewing, or otherwise either upon the outer or the inner surface of the stocking and that various other forms may be devised to suit the particular form of attaching device in connection with which the same is to be used, it being merely essential that the said portions be so secured to the stocking as to permit of their being easily grasped between the fingers for securing the same to the attaching devices and that their shape and method of

attachment to the stocking be such as will most effectually distribute the strain.

Having thus described my invention, what I claim as new, and desire to secure by Letters Patent, is—

- 5 1. A stocking having secured thereto an attaching portion for a garter-clasp provided with upwardly-divergent sides to distribute the strain upon the stocking material.
- 10 2. A stocking having at its upper end attaching portions for garter-clasps, said attaching portions diverging from their lower central points toward their upper edges to distribute the strain upon the stocking material.
- 15 3. A stocking having attaching portions imposed thereon adjacent to its upper end, and having inclined sides, secured to said stocking, and a horizontal upper edge free therefrom, substantially as specified.
- 20 4. A stocking having a plurality of attaching portions imposed thereon having inclined sides secured along the edges of said inclined sides to said stocking, and horizontal upper edges arranged parallel with the upper edge of the stocking, substantially as specified.
- 25 5. A stocking having a plurality of attach-

ing portions of triangular outline imposed thereon and incorporated into the same, and 30 united at their inclined edges with said stocking, and having their bases on a line with the upper edge of the stocking but free therefrom, substantially as specified.

6. The combination in a hose of a leg portion having a top edge or open end in a plane transverse to the general axial line of the limb of the wearer when the hose is in use, of a pair of attaching devices carried thereby and having lines of securement on the leg adjacent to and below such top and diverging theretoward and ending in free edges at the edge of the said leg portion and adapted when engaged by a fastener and under the influence of a supporter to circumferentially 45 constrict the said top edge of the leg portion upon the leg of the wearer in said plane, substantially as specified.

Signed at the city of New York, in the county and State of New York, this 7th day 50 of October, 1903.

JOHN H. FEDDEN.
